UNITED STATES PATENT OFFICE.

SIGVORT O. HAGEN, OF MINNEAPOLIS, MINNESOTA.

VALVE.

Application filed May 1, 1920. Serial No. 378,289.

To all whom it may concern:

Be it known that I, SIGVORT O. HAGEN, a citizen of the United States, residing at Minneapolis, in the county of Hennepin and State of Minnesota, have invented a new and useful Valve, of which the following is a specification.

It is the object of this invention to provide novel means whereby the supply of steam to a radiator may be controlled by air pressure, responsive to a thermostat.

The invention aims, specifically, to improve the valve mechanism which controls the flow of steam to the radiator or like device.

It is within the province of the disclosure to improve generally and to enhance the utility of devices of that type to which the invention appertains.

20 In the accompanying drawings:—

Figure 1 shows in side elevation, a device constructed in accordance with the invention, the view being diagrammatic to some extent, and illustrating the application of 25 the structure hereinafter claimed; Figure 2 is a vertical section taken through the valve casing and attendant parts, portions appearing in section; Figure 3 is an elevation looking at the bottom of the valve; and 30 Figure 4 is a fragmental sectional view, similar to Figure 2 but showing a slight modification.

Referring to Figures 1, 2 and 3, the numeral 1 denotes, generally, a valve casing, the 35 valve casing including a tubular body 2 having an outlet 3 and an inlet 4, the inlet and the outlet being rotated as occasion may require. A connection 5 unites the outlet 3 with a radiator 6. A steam line 7 is connected to the inlet 4. A partition 8 extends across the 40 body 2 of the valve casing and is located between the inlet 3 and the outlet 4, the partition 8 having an opening into which is threaded a seat 9 having a flange 10 cooperat- 45 ing with the upper surface of the partition.

A top 11 rests on the upper end of the body 2 and carries a combined guide tube and conduit 12 which projects both above and below the top, the tube 12 being closed at its 50 lower end, as shown at 14. Stated differently, the tube 12 may be described as being provided intermediate its ends with an out- 55 standing disk, represented by the top 11. The tube 12 has side ports 15 located relatively near to the closed end 14 of the tube. A lid 16 is threaded at 17 on the body 2 and

bears, as indicated at 18, on the top 11, to hold the top on the end of the body 2. One end of the tube 12 projects through the lid 16. A nut 19 is threaded on the projecting 60 end of the tube 12 and engages the lid 6 to hold the parts rigidly assembled. An elbow 20 is threaded into the upper end of the tube 12 and forms part of an air pressure line 21, in which a thermostatic valve 22 is 65 interposed.

An expandible member, such as a metal bellows 23, is located within the body 2, the upper end of the bellows being secured to the disk 11, the bottom of the bellows being 70 indicated by the numeral 24. The numeral 25 marks a valve adapted to cooperate with the seat 9, the valve 25 having depending 75 rectangularly arranged wings 26 which, being slidably received in the seat 9, serve to 80 guide and direct the movement of the valve 25, without interfering with the passage of steam through the seat 9 when the valve 25 is raised, as shown in Figure 2 of the drawings. The valve 25 has a neck 27 carrying 85 a broadened head 28 abutting against the bottom 24 of the bellows 23. A stem 29 projects from the head 28 and passes upwardly through the bottom 24 of the bellows 23, the stem being slidably received in 90 the lower end 14 of the tube 12. A nut 30 is threaded on the stem 29 and cooperates with the upper surface of the bottom 24 of the bellows 23. Thus, the valve is connected 95 to the bellows 23 to move therewith. A nut 31 is threaded on the upper end of the stem 29 and is located in the tube 12. A compression spring 32 surrounds a portion of the stem 29, one end of the spring abutting against the end 24 of the tube 12, the other end of the spring abutting against the nut 31.

In practical operation, the spring 32 elevates the valve 25 and compresses the bellows 23, the construction being such that steam may pass from the line 7, through the 100 seat 9 and into the radiator 6, by way of the connection 5. The thermostatic valve 22 may be set to permit the passage of air under pressure through the line 21, at any given temperature. When that temperature 105 has been attained, the air under pressure traverses the pipe or line 21 and enters the tube 12 by way of the elbow 20. The pressure passes into the bellows 23 by way of the ports 15, the bellows is expanded and 110 the valve 25 is thrust downwardly against the seat 9, the passage of steam through the

seat 9 to the radiator 6 thus being stopped. When the temperature of the room has cooled sufficiently, the thermostatic valve 22 will cut off the supply of air to the bellows 23, whereupon the spring 32 will reassert itself and raise the valve 25 to open position, thereby permitting the steam to pass again to the radiator.

It may occur that the bellows 23 or some other part of the device may get out of order. Again, although the device may be in working order, it may be preferred to operate the valve 25 by hand. Under such circumstances, recourse is had to a mechanical means under the control of an operator, and adapted to cooperate with the stem of the valve, to seat the valve, said means being shown in Figure 4 of the drawings. In Figure 4, parts hereinbefore described, have been designated by numerals previously used, with the suffix "a". In Figure 4, the nut 19 has been removed, its place being taken by a cap 33, the air line 21 having been disconnected. Into the cap 33, a screw 34 is threaded, the same having an external hand wheel 35. The inner end of the screw 35, obviously, is adapted to cooperate with the nut 31^a on the upper end of the valve stem 29^a to effect a depression of the stem and the valve, all of which will be obvious when Figure 4 is compared with Figure 2.

Having thus described the invention, what is claimed is:

1. In a device of the class described, a casing having a seat; an expansion member carried by the casing; a valve forced by the expansion of said member to cooperate with the seat, the valve having a stem; a tubular guide carried by the casing, the stem being slideable therein, the guide communicating with the expansion member; spring means in the guide and cooperating with the stem to retract the valve from the seat and to compress the expansion member; and a fluid pressure line communicating with the guide.

2. In a device of the class described, a

casing having an inlet and an outlet; a seat between the inlet and the outlet; a lid 50 on the casing; a tube provided intermediate its ends with a disk held between the lid and the casing, the outer end of the tube extending through the lid; an expansion member carried by the disk and enclosing 55 the inner end of the tube, the inner end of the tube having a port communicating with the expansion member; a valve carried by the expansion member and cooperating with the seat, the valve including a stem slideable 60 in the tube; an abutment on the stem; and a compression spring interposed between the abutment and the tube and constituting means for moving the valve to open position with respect to the seat.

3. In a device of the class described, a casing having an inlet and an outlet; a seat between the inlet and the outlet; a disk mounted on the casing and provided with a tube extending into the casing; an expansion member carried by the disk, the tube communicating with the expansion member; a valve mounted on the expansion member and cooperating with the seat, the valve comprising a stem slideable in the tube; an abutment on the stem; and a spring interposed between the abutment and the tube and constituting means for 70 moving the valve to open position with respect to the seat.

4. A device of the class described, constructed as set forth in claim 1, and further characterized by mechanical means under the control of an operator and adapted to cooperate with the stem to seat the valve; and mechanism for assembling said mechanical means and the fluid pressure line, interchangeably, with the guide, at the will of 75 an operator.

In testimony that I claim the foregoing as my own, I have hereto affixed my signature in the presence of two witnesses.

SIGVORT O. HAGEN.
